UNITED STATES PATENT OFFICE.

JOHN J. MYERS, OF WILMERDING, PENNSYLVANIA.

FAN ATTACHMENT FOR ROCKERS.

SPECIFICATION forming part of Letters Patent No. 662,242, dated November 20, 1900.

Application filed July 7, 1900. Serial No. 22,778. (No model.)

To all whom it may concern:

Be it known that I, JOHN J. MYERS, a citizen of the United States of America, residing at Wilmerding, in the county of Allegheny and State of Pennsylvania, have invented certain new and useful Improvements in Fan Attachments for Rockers, of which the following is a specification, reference being had therein to the accompanying drawings.

10 This invention relates to certain new and useful improvements in fan attachments for rocking-chairs, and more particularly to new and novel means for automatically as well as mechanically operating a fan connected to a chair.

15 The invention particularly aims to construct a mechanism attached to one side of a rocking-chair and which is automatically operated by the rocking of the chair, causing 20 the rotation of the fan; furthermore, connecting a fan to the mechanism in such a manner that the same can be adjusted to various positions to suit the convenience of the occupant of the chair.

25 The invention further aims to construct a fan attachment for rocking-chairs which shall be extremely simple in construction, strong, durable, efficient in its operation, and comparatively inexpensive to manufacture and 30 set up, and, furthermore, one that can be automatically as well as mechanically operated.

With the above and other objects in view the invention finally consists in the novel combination and arrangement of parts to be hereinafter more fully described and specifically pointed out.

In describing the invention in detail reference is had to the accompanying drawings, forming a part of this specification, and where- 40 in like numerals of reference indicate corresponding parts throughout the several views, in which—

Figure 1 is a perspective view of a rocking-chair, showing my improved fan attachment connected thereto with the casing removed. Fig. 2 is an enlarged side elevation of the operating mechanism for rotating the fan, showing the arrangement of the cover in dotted line. Fig. 3 is a sectional view taken on 50 the line 3-3 of Fig. 2 with the cover attached. Fig. 4 is a perspective view of the lower portion of the supporting-shaft carrying a ratchet

which is engaged by a spring-pressed arm for rotating the same.

Referring to the drawings by reference-numerals, 1 indicates the base of a rocker, to which the rocking-chair 2 is connected in the ordinary manner. Secured to one side of the chair is a keeper 3, through which extends a supporting-shaft 4, carrying an elongated sleeve 5, provided at its upper end with a fan 6. The sleeve 5 is adjustably secured to the shaft 4 by means of a set-screw 7. The lower end of the shaft 4 is journaled within a bracket 8, secured to the side of the chair, and is provided with a ratchet-wheel 9.

To arrest the downward movement of the shaft 4, the latter is provided with a stop-collar 10, which engages the keeper 3.

The reference-numeral 11 indicates a worm-gear carried by the shaft 4 and is arranged between the keeper 3 and bracket 8.

Connected to the side of the chair a suitable distance below the bracket 8 is a keeper 12, through which extends an operating-shaft 75 13, provided with a bifurcated upper end, as at 14, and connected at its lower end to a miter-gear 15, supported in the bearing 16. Pivotally secured to the bifurcated end 14 of the operating-shaft 13 is an upwardly-extending arm 17, which engages within the teeth of the ratchet-wheel 9 and is retained in such position by means of the spring 18, bearing against the same and connected at its lower end, as at 19, to the operating-shaft 13. 85

The reference-numeral 20 indicates a boss secured to the side of the chair and has journaled therein the one end of a short shaft 21, carrying the bevel-gear 22, which is adapted to mesh with the miter-gear 15. The outer face 90 of the gear 21 is provided with a pinion 23, which is adapted to mesh with the toothed rack 24, connected at its lower end, as at 25, to the base 1. The rack is formed in a curvilinear manner, as shown.

The reference-numeral 26 denotes a boss secured to the side of the rocker a suitable distance below the keeper 3 and carries the one end of the shaft 27, provided with a gear-wheel 28, which is adapted to mesh with the worm 11 for rotating the shaft 4. The shaft 27 is provided with a suitable crank or handle 29 for operating the same. The casing 30 is connected to the side of the rocker and

adapted to surround the operating mechanism and is provided with suitable openings for the passage of the shafts 4 and 27 and rack 24.

5 The operation of the device is as follows: On the downward movement of the rocker the pinion engaging the rack 24 will cause the bevel-gear to rotate, transferring motion to the miter-gear for rotating the operating-shaft 13, carrying the operating-arm 17 therewith. As the same is in engagement with the ratchet 9, it will cause the rotation of the shaft 4, sleeve 5, and fan 6. Upon the upward movement of the rocker the rotation of the 10 bevel and miter gears will be reversed, so that the arm 17 will ride over the teeth of the ratchet and not transfer any motion thereto. The action of the spring 18 will tend to keep the arm 17 in engagement with the ratchet 9 15 when the shaft 4 is being rotated.

In case it is desired to operate the fan mechanically the gear-wheel 28 is rotated by means of the crank or handle 29, which, meshing with the worm-gear 11, will transfer motion to the shaft 4, sleeve 5, and fan 6.

25 It is thought the many advantages of my improved fan attachment for rocking-chairs can be readily understood from the foregoing description taken in connection with the accompanying drawings, and it will be noted that various changes may be made in the details of construction without departing from the general spirit of my invention.

Having thus fully described my invention, 30 what I claim as new, and desire to secure by Letters Patent, is—

1. In a device of the character described, the combination with the stationary base of the chair and a rack secured to said base, of 35 a rocker mounted upon the base, keepers 3, and 8 secured to the side of said rocker, an operating-shaft journaled in said keepers, a sleeve adjustably mounted on the upper end of said shaft, a fan carried by the upper end

45 of said sleeve, a ratchet-wheel secured to the lower end of the operating-shaft, a keeper 12 secured to the side of the rocker in vertical alinement with the keepers 3 and 8, a shaft 13 journaled in said keepers 12, a spring-pressed arm pivoted in the upper end of said 50 shaft 13, and engaging the ratchet carried by the operating-shaft, a miter-gear secured on the lower end of said shaft 13, a shaft 21 secured to the side of the rocker, a bevel-gear carried by said shaft and adapted to mesh 55 with the miter-gear carried by the shaft 13, and a pinion carried by said shaft 21 for engagement with the rack carried by the base, substantially as described.

2. The combination with the base carrying 60 the rack stationary with the base, of the rocker mounted on the base, keepers secured to the side of the rockers, an operating-shaft journaled in said keepers, a sleeve adjustably mounted on the upper end of said shaft, a fan carried by said sleeve, a ratchet carried 65 on the lower end of the operating-shaft, a shaft 13 rotatably supported from the side of the rocker, an arm pivoted in the upper end of said shaft, a spring for holding said arm 70 in engagement with the ratchet of the operating-shaft, a miter-gear carried on the lower end of said shaft 13, a shaft 21 rotatably supported from the side of the rocker, a bevel-gear carried by said shaft and adapted to 75 mesh with the miter-gear carried by the shaft 13, a pinion mounted on said shaft 21 for engagement with the rack carried by the base, and a case secured to the rocker for inclosing 80 said gears and pinions, substantially as described.

In testimony whereof I affix my signature in the presence of two witnesses.

JOHN J. MYERS.
